WELL REAMER

Walter A. Abegg, Los Angeles, Calif., assignor to
 Globe Oil Tools Company, Los Nietos, Calif., a
 corporation of California

Application October 2, 1936, Serial No. 103,625

14 Claims. (Cl. 255—73)

This invention relates to a well tool and relates more particularly to a well reamer having roller cutters. A general object of this invention is to provide a practical, effective well reamer embodying novel, long wearing bearing means for mounting the roller cutters.

Considerable difficulty is encountered in rotatably supporting the roller cutters of well reamers. The reamer cutters are subjected to very heavy thrusts which cause the rapid wearing of the cutter supporting bearings so that the reamers rapidly lose gauge or effective cutting diameter. Roller bearings have been employed to mount reamer cutters, but owing to the necessity of making them very small they have not proven altogether satisfactory. The teeth of the reaming cutters must be of substantial depth to be effective and the provision of the deep teeth in the cutters places a definite limitation upon the diameter of the bearings provided in the cutters, whether they be plain bearings or roller bearings. The bearings for mounting the roller cutters of reamers being small in diameter rapidly wear to permit the rapid decrease in the gauge or effective diameter of the tools.

Another object of this invention is to provide means for rotatably mounting the roller cutters of a well reamer that is very long wearing to maintain the gauge or effective cutting diameter of the reamer for a long period.

Another object of this invention is to provide a well reamer of the character mentioned in which the shafts or pins carrying the roller cutters bear on rotatable rings of large diameter so that the wear on the parts is distributed over large areas.

Another object of this invention is to provide a reamer of the character mentioned in which the bearing rings for receiving the thrusts from the cutter pins surround the shank of the reamer to present large and, therefore, long wearing thrust receiving surfaces.

Another object of this invention is to provide a reamer of the character mentioned in which the teeth of the cutters may be of the proper or maximum depth without reducing the dimensions of the bearing parts.

Another object of this invention is to provide a well reamer in which the body or shank is subjected to a minimum of wear due to the rotation of the cutters.

Another object of this invention is to provide a reamer of the character mentioned in which the bearing rings that receive the thrusts from the cutter pins are simple, inexpensive parts.

Another object of this invention is to provide an improved well reamer of the character mentioned in which the cutters and the wear receiving parts of the bearing means may be easily and quickly replaced.

A further object of this invention is to provide a well reamer that is simple and inexpensive to manufacture, assemble and recondition.

The various objects and features of my invention will be fully understood from the following detailed description of a typical preferred form and application of the invention, throughout which description reference is made to the accompanying drawing, in which:

Fig. 1 is a central longitudinal detailed sectional view of the reamer provided by this invention with a portion of the shank in elevation. Figs. 2 and 3 are enlarged transverse detailed sectional views taken as indicated by lines 2—2 and 3—3, respectively, on Fig. 1, and Fig. 4 is a transverse, detailed, sectional view taken as indicated by line 4—4 on Fig. 1.

The improved well reamer provided by this invention includes, generally, a body or shank 10, roller cutters 11 and means 12 for rotatably supporting the cutters 11 on the shank 10.

The body or shank 10 is intended to be connected in a rotary well drilling string. In accordance with the invention the shank 10 may be integral and of simple construction. In practice the shank 10 is generally cylindrical in shape and is provided at its opposite ends with means for facilitating its connection in the drilling string.

In the particular embodiment of the invention illustrated the shank 10 has a tapered socket 13 in its upper end to receive a pin of the string and has a threaded pin 14 on its lower end to thread into a socket of the string. Circumferentially spaced ears 15 project laterally or radially from the shank 10 some distance below its upper end.

There are three equally spaced ears 15. The outer ends 16 of the ears 15 may be rounded off concentrically with the longitudinal axis of the shank and the sides 17 of the ears may be tangential and merge one with the other, as illustrated in Fig. 2. An annular downwardly facing shoulder 9 is provided on the shank 10 at the lower sides 18 of the ears 15 and is preferably flat and normal with respect to the longitudinal axis of the shank. The major intermediate portion of the shank 10 below the shoulder 9 is cylindrical and may be machined.

An annular downwardly facing shoulder 19 is provided on the shank 10 some distance above its lower end. The shank 10 is provided with a central longi-

tudinal fluid passage 20 which extends through it from one end to the other.

The cutters 11 are in the nature of roller cutters for acting on the side wall of the well bore. 5 There are three roller cutters 11 of equal length and diameter. The cutters 11 are generally cylindrical and their lower portions may be of downwardly diminishing diameter. The opposite ends of the cutters 11 are preferably flat and 10 normal to the cutters' axes. Peripheral cutting teeth 21 are provided on the cutters 11 to act on the earth formation. The teeth 21 may be varied in character without departing from the invention. In the particular case illustrated the teeth 15 21 extend axially of the cutters 11 and are interrupted by longitudinally spaced annular grooves 22 in the cutters.

In accordance with the invention trunnions or pins 23 project from the upper ends of the cutters 11 and similar pins 24 project from the lower ends of the cutters. In practice the pins 23 and 25 may be integral with the cutters 11. The pins 23 and 24 are cylindrical and are concentric with respect to the longitudinal axes of the cutters. 20 The pins 23 may be somewhat longer than the pins 24. The reaming cutters 11 are arranged axially or longitudinally of the shank 10 and are disposed so that one cutter is centrally positioned below each ear 15. A vertical or axial opening 25 extends upwardly in each ear 15 from its lower surface 18 to receive the pin 23 of the adjacent cutter 11. In accordance with the invention the openings 25 receive the pins 23 with substantial clearance and merely serve to center or position 30 the pins 23 and the upper portions of the cutters. The openings 25 receive only the upper portions of the pins 23, the upper ends of the cutters 11 being spaced some distance below the ears 15. Replaceable discs or thrust bearings 26 are provided in the upper ends of the openings 25 to receive the upward thrusts from the ends of the pins 23.

The means 12 for rotatably supporting or mounting the cutters 11 includes a ring 27 surrounding the shank 10 and bearing upwardly against the shoulder 19. The ring 27 is keyed against rotation on the shank by a key 28 co-operating with grooves or notches 29 in the ring and the shank 10. A nut 30 is threaded on the shank 10 to bear upwardly against the ring 27 and hold it against the shoulder 19. The ring 27 is provided with outwardly or radially projecting ears 31. The ears 31 may be identical in cross sectional configuration to the ears 15 and are 45 vertically aligned with the ears 15. Openings 32 are provided in the ears 31 to receive the lower portions of the cutter pins 24. In accordance with the invention the openings 32 receive the pins 24 with substantial clearance so that they 50 are not worn by the pins and merely serve to position and retain the pins and the lower portions of the cutters 11. The upper ends 33 of the ears 31 are flat and normal to the longitudinal axis of the shank 10.

60 The cutter mounting means 12 further includes a rotatable bearing ring 34 surrounding the shank 10 at the under sides of the ears 15 and the shoulder 9 and a rotatable bearing ring 35 surrounding the shank 10 at the upper sides of the ears 31 and the ring 27. The bearing rings 34 and 35 are important elements of the invention. The rings 34 and 35 are provided to receive the heavy radial thrusts from the cutters' pins 23 and 24, respectively, to support the cutters 11 against the inward operating forces. The

5 bearing rings 34 and 35 are hardened to be long wearing and are freely rotatable on the shank 10. The upper ring 34 has a flat upper surface that may bear on the shoulder 9 and the ring 35 has a flat lower surface that may bear on the upper 10 end 33 of the ring 27. The ring 34 is positioned between the shoulder 9 and the upper ends of the cutters 11 and the ring 35 is positioned between the lower ends of the cutters 11 and the ring 27. The rings 34 and 35 are provided with 15 cylindrical peripheries and the cutter pins 23 and 24 have rotative or rolling contact with the rings. The ring 34 is located to be engaged by the exposed portions of the cutter pins 23 and the ring 35 is engaged by the exposed portions of the pins 24.

The bearing rings 34 and 35 may be alike in diameter and are proportioned to support the pins 23 and 24 against inward thrusts or forces so that the pins do not bear on the walls of the 20 openings 25 and 32 for the transmission of these forces. The bearing rings 34 and 35 may have some clearance with the shank 10 and are maintained centralized through their cooperation with the circumferentially spaced pins 23 and 24. The 25 rolling contact of the pins 23 and 24 with the rings 34 and 35 causes rotation of the rings with respect to the shank 10. Thus the rings 34 and 35 act as large roller bearings for the pins 23 and 24 of the cutters 11. It will be observed 30 that the rings 34 and 35 surround the shank 10 to have peripheral surfaces of large diameter. The wear resulting from rotation of the cutters 11 during operation of the reamer is distributed 35 over the large peripheral areas of the bearing rings 34 and 35. The rings 34 and 35 presenting large wear receiving surfaces are very long wearing and support the cutters 11 in operative positions to maintain the reamer to gauge for a much longer period than the bearings heretofore employed. 40

During operation of the reamer the shank 10 connected in the drilling string turns with the string. The cutters 11 are positioned to have 45 rolling or reaming contact with the earth formation at the side wall of the well bore. The engagement of the cutters 11 with the formation results in rotation of the cutters about their own axes. As described above, the bearing rings 34 and 35 support the cutters 11 against inward 50 thrusts or forces through their engagement by the cutter pins 23 and 24. The engagement of the rotating pins 23 and 24 with the peripheries of the rings 34 and 35 results in rotation of the rings relative to the shank 10. As the rings 34 55 and 35 rotate they constantly present new peripheral surfaces for engagement by the cutter pins so that the wear resulting from the engagement of the pins with the rings is evenly distributed throughout the circumferences of the 60 bearing rings. The rings 34 and 35 are large in diameter and the wear is evenly distributed throughout the circumferences of the rings so that the rings are very long wearing. The bearing rings tend to gear the several cutters together 65 preventing the cutters from sliding on the formation and from becoming flattened. The rings 34 and 35 operate to support the cutters 11 to ream the bore to gauge for a very long period. Upward thrusts on the cutters 11 are taken by the 70 bearings 26 and the upper ends of the cutters need not contact the ring 34 to interfere with its rotation.

The cutters 11 and the various bearing parts may be easily and quickly removed for replace- 75

ment. Upon the unthreading of the nut 30 the ring 27 may be slid from the shank 10 to free the cutters 11 and the rings 34 and 35 so that they may be easily disengaged from the shank 10. 5 The shank 10 and the various other parts of the reamer are extremely simple and inexpensive to manufacture.

Having described only a typical preferred form 10 and application of my invention, I do not wish to be limited or restricted to the specific details herein set forth, but wish to reserve to myself any variations or modifications that may appear to those skilled in the art or fall within the scope 15 of the following claims.

15 Having described my invention, I claim:

1. A well reamer including, a shank, roller cutters spaced about the shank, pins projecting from the opposite ends of the cutters, and rotatable rings surrounding the shank and engaging the 20 pins to receive the inward thrusts from the pins.

2. A well reamer including, a shank, roller cutters spaced about the shank, pins projecting from the opposite ends of the cutters, means receiving the pins to hold the cutters properly positioned, and rotatable rings surrounding the shank and contacting the pins to receive the 25 inward thrusts from the pins.

3. In a well reamer having a shank and roller cutters spaced around the shank, the combination 30 of, a rotatable ring surrounding the shank, and parts on the cutters having thrust transmitting engagement with the ring.

4. In a well reamer having a shank and roller cutters spaced around the shank, the combination 35 of, spaced rotatable bearing rings surrounding the shank, and axially spaced parts on the cutters having thrust transmitting engagement with the rings.

5. In a well reamer having a shank and roller cutters spaced around the shank, the combination 40 of, spaced rotatable bearing rings surrounding the shank, and axially projecting end parts on the cutters having thrust transmitting engagement with the rings.

45 6. A well reamer including, a shank, roller cutters, means retaining the cutters in spaced relation about the shank for free rotation, and rotatable bearing rings around the shank having cooperation with the cutters to receive the inward thrusts therefrom.

7. A well reamer including, a shank having 50 openings, roller cutters, means retaining the cutters in spaced relation about the shank for free rotation including trunnions on the ends of the cutters freely fitting the openings in the shank, and bearing rings surrounding and bearing on the shank and having cooperation with the trunnions to receive the inward thrusts therefrom.

8. A well reamer including, a shank having 55 openings, roller cutters, means retaining the cutters in spaced relation about the shank for free rotation including trunnions on the ends of the cutters received in the openings in the shank, and bearing rings surrounding the shank for free rotation thereon and having cooperation with the trunnions to receive the inward thrusts therefrom.

9. A well reamer including, a shank, roller cutters, means retaining the cutters in spaced

relation about the shank for free rotation, spaced parts on the shank having aligned openings, and pins rigid with the cutters and projecting from their ends to freely extend into said openings, and rotatable bearing rings surrounding the shank and cooperating with the pins to receive the inward thrusts therefrom. 5

10. A well reamer including, a shank, roller cutters, means retaining the cutters in spaced relation about the shank for free rotation, spaced 10 parts on the shank having aligned openings, at least one of said parts being removable to permit the arrangement of the cutters between the parts, means for holding the part against movement on the shank, and pins rigid with the cutters and 15 projecting from their ends to freely extend into said openings, and bearing rings surrounding and rotatable on the shank and cooperating with the pins to support them against inward pressures.

11. A well reamer including, a shank, circumferentially spaced ears on the shank, a member surrounding the shank in spaced relation to the ears, the ears and member having axially aligned 20 openings, spaced roller cutters between the ears and member, pins rigid with the cutters and projecting from their ends to extend into said openings, and bearing rings surrounding and bearing 25 on the shank and having their peripheries in cooperation with the pins to receive their inward thrusts. 30

12. A well reamer including, a shank, circumferentially spaced ears on the shank, a member surrounding the shank in spaced relation to the ears, said member being removable from the shank, a part threaded on the shank to hold said 35 member in place, the ears and member having axially aligned openings, spaced roller cutters between the ears and member, pins rigid with the cutters and projecting from their ends to extend into said openings, and bearing rings surrounding 40 and carried by the shank and having their peripheries in cooperation with the pins to receive the inward thrusts therefrom.

13. A well reamer including, a shank, circumferentially spaced ears on the shank, a member 45 surrounding the shank in spaced relation to the ears, the ears and member having axially aligned openings, spaced roller cutters between the ears and member, pins rigid with the cutters and projecting from their ends to extend into said 50 openings, said member being removable axially along the shank to allow insertion and removal of the cutters, a nut on the shank locking the member against movement, and rotatable bearing rings around the shank cooperating with the 55 pins to receive the inward thrusts therefrom.

14. A well reamer including a shank having a circumferential series of projecting ears and a cylindrical portion extending axially from said series, a member around the shank in spaced relation to the ears, the ears and member having openings, roller cutters spaced about the shank, pins rigid with the cutters and extending into said openings, and rotatable bearing rings around the cylindrical portion of the shank cooperating 60 with the pins to receive the inward thrusts therefrom. 65
